UNITED STATES PATENT OFFICE.

JACOB J. BYERS, OF CHICAGO, ILLINOIS, ASSIGNOR TO THE NATIONAL MALLEABLE CASTINGS COMPANY, OF CLEVELAND, OHIO, A CORPORATION OF OHIO.

TRACK-FASTENER.

1,164,620.

Specification of Letters Patent. Patented Dec. 14, 1915.

Application filed October 5, 1914. Serial No. 865,031.

To all whom it may concern:

Be it known that I, JACOB J. BYERS, a citizen of the United States, residing at Chicago, Cook county, Illinois, have invented 5 new and useful Improvements in Track-Fasteners, of which the following is a specification, reference being had to the accompanying drawings, in which—

Figure 1 is an elevation showing my improved track fastener in the form of a rail anchor or anti-creepers applied to a rail; Fig. 2 is a plan of my fastener showing the locking member in driven position; Fig. 3 is a section on line III—III of Fig. 1, but 10 with the locking member only partially driven in; Fig. 4 is a section on lines IV—IV of Fig. 2, and Fig. 5 is a detail of the locking member.

My invention relates to track fasteners 20 and consists in a two-part device having a wedging and frictional engagement with the base flanges of a rail.

My invention also consists in the construction and coöperation of the parts which 25 I shall hereinafter describe and claim.

Referring to the drawings, in which I have illustrated my invention as being applied to a rail-anchor or anti-creepers, A indicates the rail, B the base plate, C the 30 wedge member and D a railroad tie. The base plate B is provided with oppositely-disposed lugs 2 and 3, reinforced by the vertically-extending ribs 4 on the under side of the plate B. On the lug 2 are formed 35 wedging surfaces 5, 5', intended to grip the upper and lower surfaces of one of the rail flanges 6. The lug 3 has on the side toward the rail a surface 7, concave in vertical section, as is shown in Figs. 1 and 4, and convex in horizontal section, as is shown in 40 Figs. 2 and 3. The base plate B is also provided with a downwardly-extending foot or brace 8, intended on its outer surface to bear against the tie D, to prevent movement of 45 the anchor in a direction toward the tie. The wedge member C has a curved wedging surface 9, corresponding to the curvature of the surface 7 against which it bears. On the opposite side the wedge C is provided 50 with a longitudinally-extending slot 10 having wedging and gripping faces 11, 11', to take about the upper and lower faces of the flange 6' of the rail, as is shown in Figs. 1 and 4. The lateral depth of the slot 10 de-

creases toward the forward or wedge end 55 12 of the wedge C, because of the convergence of the inner surface 13 of the slot 10 and the outer edges 14, until at the point 15 the surface 13 and the wedge edge 14 almost coincide, the wedge member at the 60 point 15 presenting a flat, vertically-disposed surface, which bears against the lateral edge 16 of the rail base, as is shown in Figs. 2 and 3. The opposite or driving end of the wedge C is formed into a head or 65 abutment 17, by means of which it is driven into locked position.

The anchor is applied to the rail in the following manner: The base plate B is first applied from below the rail by bringing the 70 abutment 2 over the flange 6 of the rail, and the plate B is then tilted upward, until it rests against the under side of the base of the rail and the foot or brace 8 bears against the tie D. The wedge end 12 of the member C is then inserted between the surface 7 of the abutment 3 and the edge 16 of the rail flange 6'. It is then driven longitudinally toward the foot 8 by blows delivered 75 against the driving head 17. It will be seen 80 that when the wedge end 12 is first inserted in the guideway between the surface 7 and the edge of the rail flange 6', and before wedging action takes place between the parts, it is in the position indicated in dotted lines in Fig. 2. As the wedge C is driven in its axis is revolved slightly as it moves forward, and finally assumes, when it has 85 been driven home, the position shown in full lines in Fig. 2. This rotating movement is 90 caused by the convex surface 7 on the abutment 3, the corresponding surface 9 on the wedge member C and the engagement of the edge 16 of the rail by the surface 13 at the forward end 12 of the wedge as it is driven 95 in. The curved surface 9 of the wedge slides along the surface 7, thus rotating the wedge as it is driven in, and this rotation forces the wedging surfaces 11, 11' of the wedge to grip the flange 6' of the rail, as is shown 100 in Figs. 1 and 4. The wedging end 12, as the wedge is driven in, by its contact at the point 15 with the edge 16, will force the rail laterally into wedging engagement with the surfaces 5, 5' of the abutment 2, while the 105 surfaces 11, 11' of the wedge C will hold the wedge firmly to the flange 6' of the rail. When the wedge has been driven home it

will have a three-point contact with the rail. The surface 15 of the wedge will frictionally engage the edge 16 of the rail flange 6' while the surfaces 11, 11' will engage the 5 top and bottom of the rail flange. The surfaces 5, 5' of the base plate B and the surfaces 11, 11' and 15 of the wedge C will frictionally engage the flanges 6, 6' of the rail and hold it from creeping, and the 10 wedging contact of the wedge end 12 against the edge 16 of the rail will hold the wedge in position and maintain the wedging action between these surfaces and the rail, regardless of vibration. It will be seen that as 15 the wedge C is driven in, wedging contact with the rail will first occur at the point 15, and as the wedge is driven in farther the pressure of the point 15 against the rail will cause the wedge to tip or rotate upon the 20 surfaces 7 and 9, as is shown in the various positions indicated in Figs. 2 and 3. When the wedge has been driven to final locked position the gripping engagement of the wedge with the flange of the rail and the 25 wedging engagement of the wedge end 12 against the rail at the point 15 are substantially equalized, due to the fact that the wedging angle of the end 12 with the curved surface 7 is more acute than the wedging angle between the rear end of the wedge and the curved face 7. When it is desired to 30 remove the anchor, the wedge is driven rearwardly and out of engagement with the rail, and the plate B may then be disengaged from the rail and tie.

It is obvious that my improved track fastener may be utilized in a variety of applications and that modifications may be 35 made in the construction which I have shown and described herein, without departing from my invention.

What I claim is:

1. A track fastener consisting of a base-plate, a wedge, a convex surface on the base-plate, a concave surface on the wedge, and 45 a bearing on one end of the wedge against the edge of the rail flange, the other end being adapted to grip the upper and lower surfaces of the flange of the rail, the wedge being adapted to be driven in between a 50 flange of the rail and the base-plate and to be tilted about the convex surface of the base-plate, and to be driven into locked position.

2. A rail anchor comprising a base member having upwardly-extending projections on opposite sides of the base of the rail, and a wedge member adapted to be driven between one of said projections and the base of the rail, said wedge having a rocking 60 bearing against said projection while being driven, and having, when in driven position, an engagement at one of its ends with the upper and lower surfaces of the rail-base and being out of contact at that end with 65 the edge of the rail-base, and having at its other end an engagement with the edge of said rail-base.

3. A track fastener comprising two relatively movable parts, each of said members 70 engaging the base of the rail and one of said members having a V-shaped jaw engaging the top and bottom of the rail and out of contact with the edge of the rail at one portion, and in contact with the edge of the 75 rail and out of wedging engagement with its top and bottom at another portion.

JACOB J. BYERS.
